P. J. HINDMARSH.
FENCE POST.
APPLICATION FILED JUNE 23, 1915.

Patented Feb. 1, 1916.

Fig. 6.

UNITED STATES PATENT OFFICE.

PERCY J. HINDMARSH, OF LINCOLN, NEBRASKA, ASSIGNOR TO THE AMERICAN STEEL & WIRE COMPANY OF NEW JERSEY, OF HOBOKEN, NEW JERSEY, A CORPORATION OF NEW JERSEY.

FENCE-POST.

1,169,823.

Specification of Letters Patent.

Patented Feb. 1, 1916.

Application filed June 23, 1915. Serial No. 35,771.

To all whom it may concern:

Be it known that I, Percy J. Hindmarsh, a citizen of the United States, and resident of Lincoln, in the county of Lancaster and State of Nebraska, have invented certain new and useful improvements in Fence-Posts, of which the following is a specification:

My invention relates to fence posts and has particular reference to a novel corner post and means for anchoring the same in the ground.

In the construction of the post I utilize a tubular post member and an anchor member in the form of a cruciform bar having a flared and pointed lower end, the object being to provide means whereby the anchoring member may be readily driven and the post driven thereover, the arrangement being such that the lower end of the post is flared outwardly, and during such flaring operation the dirt is caused to pack between the anchor and the tubular post to securely hold the two in engagement. The necessity for this arises for the following reasons: After the post has been driven and the lower end properly flared, unless means are provided for holding the anchoring member and the post in engagement, the post has a tendency to rise under draft, the flukes which were previously formed becoming straightened out, leaving the spreader in its original position. This is overcome by uniting the two by frictional engagement of the soil. The reason why these flukes have a tendency to straighten out is because of the fact of their disposal at substantially right angles to the plane of the post, therefore giving a greater leverage tending to straighten them out and also because of the fact that the section of metal at the point of the bend is less than at any other point, this being necessary to secure the proper bending action.

A still further object is to extend the wings of the spreader out as far as possible, in order to give support for the flukes at a point as near as possible to their ends, thus reducing the leverage tending to rebend the same. The holding engagement between the spreader and the post is secured by the simple expedient of providing a stop for the soil which has a tendency to rise between the spreader and the post.

My invention also comprises a novel brace

for use in connection with an end post of this description.

The invention will be more readily understood by reference to the accompanying drawings wherein—

Figure 1 is a vertical section through a post and spreader, the spreader having been driven and the post having been driven thereover to the point where the lower end thereof is about to be spread by continued driving of the post; Fig. 2 is a similar view showing the post in its driven position; Fig. 3 is a section on the line 3—3 of Fig. 1; Fig. 4 is a section on the line 4—4 of Fig. 1; Fig. 5 is a section on the line 5—5 of Fig. 1; and Fig. 6 is an enlarged perspective view of the spreader.

Referring more particularly to the drawings, it will be seen that I provide a post 10, preferably of tubular form, the lower end of which is slotted a short distance to provide four portions which may be spread outwardly to form flukes. At the point of the termination of the slits I drill small holes 11. This serves to reduce the section of metal at this point and to insure its proper bending. The spreader 12 is preferably of cruciform cross section and is provided with a driving head 13 and a flared lower end consisting of webs 14 projecting outwardly from each web of the cruciform shank thereof; these webs or wings, as indicated in Figs. 1 and 2, extend outwardly a material distance. The upper edge of the webs 14 are preferably curved at the point of junction with the body of the spreader in order to give the proper flare or bend to the lower end of the post when it is driven thereover. The degree of curvature can be readily determined by experiment. As will be seen, the space between the adjacent webs 14 is open, providing ready access for the soil between the different webs of the shank, thus permitting the soil to surround the shank of the spreader as it is being driven. At a point near the upper end of the spreader I provide stops 15, as best shown in Fig. 3, which substantially close the passage between the webs of the cruciformed member. The object in the provision of these stops is as follows: The spreader is driven until the stops 15 are practically level with the surface of the ground. This serves as a gage to determine the proper point to drive the spreader.

Thereafter the post is driven over the spreader and the spreader is not disturbed materially until the lower end of the post contacts the webs 14. The continued driving on the post serves to flare the lower end of the post and at the same time to drive the spreader deeper into the ground, as indicated in Fig. 2. The soil which occupied the space between the webs of the spreader 5 when driven, of course, remains in place after the post has been driven thereover. Continued driving of the post and spreader forces more soil into the post and as the spreader is likewise driven to a certain extent and the soil is unable to rise higher than the stops 15, the soil is rigidly packed on the interior of the post and the spreader and post are rigidly held against movement, due to frictional engagement of the soil, 10 the parts finally reaching the position of Fig. 2. The necessity for this, as heretofore described, is in order to provide a support for the flukes of the post without corresponding elevation of the spreader. It 15 will be seen that if the post is permitted to rise and the spreader to remain in its position, there will be no support to prevent the flukes from straightening out or from being broken because of the leverage of the flukes. Furthermore, the packing of the soil as 20 described, has the added function of preventing further descent of the spreader which would occur if no resistance were offered to such further descent. The soil not only 25 packs in the interior of the post, but also around the lower end of the spreader and, therefore, assists in spreading the flukes and providing a solid base on which they rest. This is particularly essential and 30 desirable where the post is installed in soft ground.

In order to provide an indication when the post has been properly located, that is, when the flukes have been spread to the most 45 advantageous point, I locate a hole 16 in the side of the post through which the upper end or driving head 13 of the spreader may be seen.

As described, I provide but four of the 50 webs 14, thus leaving a space through which the soil may enter the post. By the provision of four of these webs and by slitting the post to provide four flukes, it might be possible that the webs would in some instances register with the slits and no spreading action occur. I obviate this, as shown in Fig. 5, by flattening one side 17 of the post for a short distance near the lower end.

The post, as described heretofore, will be 60 found to be efficient in service for several reasons, not the least of which is in that the anchoring or spreading member serves likewise as a support for the post from its lowest point to a point considerably above the 65 surface of the ground. This gives the

strengthening effect at the point where most needed and results in a construction having a strength equal to that of a post which is much heavier. By the use of a light post driving becomes much easier than would be 70 possible with a post of a size corresponding to that of the strength secured in the present construction.

I claim:

1. In a fence post, the combination of a 75 spreader of angular cross section and provided with wings at its lower end, said spreader being provided with a transverse web near its upper end, and a tubular post adapted to be driven over said spreader, substantially as described.

2. In a device of the class described, the combination of a spreader of angular cross section and provided at its lower end with wings corresponding to the webs of the 85 spreader, a transverse wall near the upper end of said spreader, and a tubular post adapted to be driven over said spreader, substantially as described.

3. In a device of the class described, the 90 combination of a spreader of cruciform cross section and provided with wings at its lower end, one for each of the webs of the shank of the spreader transverse webs uniting the vertical webs of said spreader, and a tubular 95 post having a slotted lower end and adapted to be driven over said spreader, the wings on said spreader being adapted to cause the lower end of said post to flare and the transverse webs being adapted to cause the soil 100 to pack between the post and the spreader, substantially as described.

4. In a device of the class described, the combination of a spreader of cruciform cross section and provided with wings at its 105 lower end, the number of said wings corresponding to the number of webs in the shank of said spreader, transverse webs uniting the longitudinal webs of the spreader near the upper end thereof, and a tubular post, the lower end of which is slotted and adapted to be flared upon being driven over said spreader, substantially as described.

5. In a device of the class described, the combination of a spreader of cruciform cross 115 section, and a tubular post adapted to be driven thereover, said post being flattened on one side near its lower end to prevent relative rotary movement between the spreader and the post, substantially as described.

6. In a device of the class described, the combination of a spreader adapted to be driven into the ground, leaving a portion of the upper end thereof projecting above the ground, said spreader being provided with a 125 transverse web, said web acting as an indicator of the point to which said spreader should be driven, and a tubular post adapted to be driven over said spreader, the lower end of said spreader and post being open 130

to permit the entrance of soil to the interior of the tube, said web near the upper end of the spreader serving as a stop to prevent further upward movement of the soil and to 5 thereby cause the packing of the soil within the post, substantially as described.

7. In a device of the class described, the combination of a spreader having a driving head adapted to project above the surface 10 of the ground after said spreader has been driven, the lower end of said spreader being flared, and a tubular post having a slotted lower end adapted to be flared by said spreader, said post being provided with an 15 aperture 16 in its side wall through which the upper end of said spreader may be observed to determine the proper point to which said post should be driven, substantially as described.
8. In a device of the class described, the combination of a spreader of cruciform cross section, the lower ends of the webs of said spreader being flared, a tubular post having 20 a slotted lower end adapted to be driven over

said spreader, and means for packing the 25 soil into the post during the driving action to prevent relative movement between the post and spreader, the flared portion of the spreader being caused to underlie the flukes formed on the post by the driving action and 30 to remain in contact therewith in order to support the same during upward strains on the post, substantially as described.

9. In a device of the class described, the combination of a spreader of cruciform cross 35 section and provided with four wings at its lower end, said wings corresponding to the webs of the spreader, a tubular post, the lower end of which is slotted to provide four flukes, and means for preventing the registering of the slits in said tube and the wings on said spreader, substantially as described.

Signed at De Kalb, Ill., this 9th day of June, 1915.
